UNITED STATES PATENT OFFICE.

GEORGE C. SIEBERT, OF CHICAGO, ILLINOIS.

HORSESHOE.

1,149,223.

Specification of Letters Patent. Patented Aug. 10, 1915.

Application filed December 14, 1914. Serial No. 877,145.

To all whom it may concern:

Be it known that I, GEORGE C. SIEBERT, a citizen of the United States, and a resident of the city of Chicago, in the county of Cook and State of Illinois, have invented a certain new and useful Improvement in Horseshoes; and I do hereby declare that the following description of my said invention, taken in connection with the accompanying sheet of drawing, forms a full, clear, and exact specification, which will enable others skilled in the art to which it appertains to make and use the same.

My invention relates generally to improvements in horseshoes, and it consists, essentially, in the novel and peculiar combination of parts and details of construction, as hereinafter first fully set forth and described and then pointed out in the claims.

In the drawing already referred to, which serves to illustrate my said invention more fully, Figure 1 is a bottom plan of my improved shoe. By bottom plan, I refer to that face of the shoe which contacts with the ground, or, in other words the tread. Fig. 2 is an elevation of the rear or heel end of the shoe in inverted position. Fig. 3 is a vertical section in line 3—3 of Fig. 1. Fig. 4 is a like section in line 4—4 of Fig. 1. Fig. 5 is a similar section in line 5—5 of Fig. 1.

Like parts are indicated by similar characters or symbols of reference in all the figures of the drawing.

My invention has general reference to horseshoes of the bar type, and relates particularly to that class of bar shoes possessed of soft treads and connecting bars constructed of yielding material, such as rubber and the like; and, the essence of my invention resides in new and novel means for anchoring the said yielding bar to the underface of the body of the shoe at the rear ends thereof; to prevent the same from becoming loosened; and correlated to these means are other means surrounding the greater portion of the yielding bar at both ends thereof, to eliminate the spreading tendency of said bar when in use. The yieldable nature of rubber and rubber compounds is well known, and in the majority of shoes of the yielding bar type, the bar entirely envelops the rear ends of the shoe, or is directly vulcanized to the under or upper face thereof, so that there is no resistance to the

spreading tendency of the rubber composition while under the pressure to which it is subjected after the shoe is applied to a horse's hoof. This constant pressure soon causes a flattening of the yielding bar and a segregation of the rubber mass, rendering the bar of no further value for the purpose for which it was intended; *i. e.* a cushion for the horse's hoof at the frog and heel thereof. In the practice of this present invention, however, the spreading, flattening, and segregation of the rubber bar is eliminated, as the ends of the bar, where practically the total weight is sustained, are entirely surrounded by calks depending from the under face of the body of the shoe, so that all pressure upon the bar results in an intensification of the rubber mass between the said calks, rather than a segregation thereof.

To better understand my invention, reference is now made to the drawing in which A indicates the horse shoe as a whole, which is of conventional conformation, being substantially of U-shape in plan with converging rear ends A'—A'', which ends are generally termed the heel of the shoe, while that portion A''', located in the center of the U-shaped configuration is known as the toe thereof.

The base or body of the shoe is indicated at B and is of the aforesaid conformation with its rear converging portions B', B'' widened for a proper distance forward of the rear ends A' and A'', which rear ends are rounded as at 10 and 10^a. Around the inner outline of body B, beginning and terminating a short distance from the extremities of the widened portions B' and B'', there is formed integrally with the body B a continuous upstanding calk 12; *i. e.*, depending when the shoe is in use. And parallel to this calk, outwardly thereof and spaced therefrom and forming a channel 12^a therebetween, is a like calk 13, which calk, however, merges into a heavy toe calk 13^a at the toe portion A''', of the shoe. Said calk 13 turns outwardly abruptly at 14 and 14^a, then continues along the outer edges of the widened portions B' and B'', and partially around the rounded rear ends A' and A'' thereof, as clearly seen in Fig. 1. It will thus be observed that the calks 12 and 13 form confining receptacles or spaces 15 and 15^a at the widened portions B' and B'' for the reception of the ends 16 and 16^a of a

transverse rubber bar C connecting the ends of the shoe, the outer edges of said bar ends being embraced by the calk 13, as clearly seen in Figs. 1 and 2, and the inner edges 5 thereof embraced by the calk 12, the extreme ends of which calk are, however, bent inwardly at 17, as seen in Fig. 4, so as to form a positive anchorage.

Pierced from the body B, in the portions 10 B' and B'', and bent in a direction toward the tread of the shoe, are arcuate prongs 17^a and 17^b, which are anchored in the ends 16 and 16^a of the yielding bar C, these prongs providing additional anchorages, preventive of the loosening of said bar from the body of the shoe. The rear edge of the bar C is concaved at C' between the ends A' and A'' while its forward edge thereof is 15 convexed as at C'', the reason for which may 20 now be explained as follows:

Horseshoes when made in quantities in factories devoted to that class of goods are produced in definite sizes as to breadth and length, and are sold to jobbers, and thence to 25 the horseshoers. It is seldom that the feet of a single animal are alike, and much less so in the case of a plurality of animals. Therefore means must be provided whereby a shoe of any particular size may be varied 30 in width to fit a hoof of nominally that size. Sometimes the widened portions B' and B'' and the rear ends A' and A'' must be made narrower in overall width and in other instances the width must be increased. As 35 hereinbefore described, the yielding bar C is irremovably anchored at its respective ends 16 and 16^a in the spaces 15 and 15^a, and the yielding material thereof therein confined; therefore, if it be necessary to widen a shoe, 40 pressure by means of a light screw jack is applied at the points 100 and 101 on the interior of the shoe. The yielding material, being securely confined at its ends within the rear portions of the shoe, will of necessity follow those portions thereof as they 45 are widened out; wherefore the necessary stretch of the yielding material of the bar is provided for by a flattening of the concave and convex curves C' and C''. If the requirements 50 are such that the shoe needs to be narrowed, the body thereof is drawn together by suitable clamps applied at 102 and 103, in which case the surplus material in the yielding bar finds expression in an 55 increase in the concavity and convexity C' and C'' of the bar C, in an evident manner.

The preferred process of affixing the yielding bar C to the body B may now be broadly disclosed as follows: Generally 60 speaking, the body B is first placed in a mold having a cavity adapted to receive said body. Said mold has a top half containing a cavity of the shape of the yielding bar. Semi-plastic rubber or rubber compound is 65 now placed in the spaces 15 and 15^a by hand

and sufficient material supplied to form the complete bar C. The top half of the mold is then placed in position; a strip of canvas 104 being placed adjacent the body B, and the halves of the mold tightly bolted together, after which the mold and its contents is placed in a suitable vulcanizer to suitably vulcanize and cure the rubber. This done, the shoe is removed from the mold, when it will be found that the projections 17^a and 17^b, and the inwardly curved portion 17 of calk 12 have been securely anchored within the bar C; that the said rubber compound is thoroughly secured in the widened portions B' and B'', and that no portion of the rubber compound has passed to the reverse side of the shoe, this being prevented by the aforementioned canvas strip 104, and it may now be added that this strip is of the same shape in plan as the bar C and is cemented to the top face of the body B, to remove metallic contact of the shoe with the heel of the animal.

It will be observed that the bar C is of greater height than the height of the calks 12 and 13 and the object of this is to afford a certain amount of compressibility to the bar in a manner easily understood.

The exterior outline 105 of the body B of the shoe A follows the outline of the calk 13, but a distance spaced therefrom, equal to, more or less, the width of the offsets 14 and 14^a. It is to be understood, however, that these minute details of construction do not form a part of my invention and may be varied at will. Through and around the body B, exteriorly of the calk 13, are produced a series of countersunk through apertures 106 for the reception of horseshoe nails (not shown) whereby the shoe is fastened 105 to the animal's hoof.

Driven into the channel 12^a, extending from the widened portion B' to the widened portion B'', there is a U-shaped, rectangular section of yieldable material 110. This material is preferably a combination of a canvas and a rubber compound, vulcanized together in strips in a plane at right angles to the plane of the base or body B. Said material is generally produced in aforesaid cross section in long lengths, and the length for each shoe is cut therefrom. Being bendable in nature, the same is shaped to the contour of the channel 12^a and driven thereinto until the surface thereof is slightly above the edge of the calks 12 and 13, and somewhat below the tread surface of the bar C.

While herein I have disclosed the preferred mode of practising my invention, I 125 reserve the right to make such changes and alterations therein as may come within the province of the skilled mechanic or permitted under the doctrine of equivalents.

Having thus fully described my invention 130

I claim as new and desire to secure to myself by Letters Patent of the United States:

1. A horseshoe including a curved body possessed of inner and outer upstanding substantially continuous calks, a filling material therein, the said body and outermost calk being widened apart at the rear ends thereof, arcuate anchorages projecting from said body, in said widened portions of said body, and a yielding bar connecting said rear ends, partially embraced by said calks, and anchored to said anchorages.

2. A horseshoe including a curved body possessed of inner and outer upstanding substantially continuous calks, a filling material therein, the said body and outermost calk being widened apart at the rear ends thereof, arcuate anchorages projecting from said body, in said widened portions of said body, and a yielding bar connecting said rear ends, partially embraced by said calks, and anchored to said anchorages, the rear ends of said inner calk having their upper edges bent toward said outer calk and projecting into said bar.

3. A horseshoe including a curved body possessed of inner and outer upstanding substantially continuous calks, a filling material therein, the said body and outermost calk being widened apart at the rear ends thereof, arcuate prongs pierced from said body in alinement to each other and projecting therefrom in opposite directions in said widened portions of said body, and a yielding bar connecting said rear ends, partially embraced by said calks, and anchored to said prongs.

4. A horseshoe including a curved body possessed of inner and outer upstanding substantially continuous calks, a filling material therein, the said body and outermost calk being widened apart at the rear ends thereof, arcuate prongs pierced from said body in alinement to each other and projecting therefrom in opposite directions in said widened portions of said body, and a yielding bar connecting said rear ends, partially embraced by said calks, and anchored to said prongs, the rear ends of said inner calk having their upper edges bent toward said outer calk and projecting into said bar.

5. A horseshoe including a curved body having inner and outer upstanding, substantially continuous calks, the rear ends of said inner calk terminating in advance of the rear ends of said outer calk and having the upper edges of said rear ends bent toward said outer calk, a filling material between said calks, the said body and outermost calk being widened apart at the rear ends thereof, alined and oppositely extending arcuate prongs in said widened portion of said body, and a yielding bar connecting said widened portions, said prongs and said bent upper edges of said inner calk projecting into said bar.

In testimony whereof I have hereunto set my hand in the presence of two subscribing witnesses.

GEORGE C. SIEBERT.
